TIMOTHY C. POMEROY, OF MINNEAPOLIS, MINNESOTA.

LIFTING JACK.

Application filed October 1, 1925. Serial No. 59,909.

This invention relates to new and useful improvements in lifting jacks particularly adapted for use in lifting the axles or wheels of automobiles, trucks, etc. and more particularly relates to such a device of the hydraulic type, using an inelastic fluid such as oil to transmit power in the operation of the jack.

An object of this invention is to provide a hydraulic jack comprising a stationary member having hollow ram or plunger reciprocally mounted therein, and provided with a simple valve mechanism controlled by the operating handle to regulate the flow of fluid therein to lower the plunger.

The particular object of this invention, therefore, is to provide an improved hydraulic jack which is an improvement over the form shown in the prior pending application by me and Carl E. Johnson, Serial Number 734,730, filed August 28, 1924.

Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow.

In the accompanying drawing forming part of this specification,

Figure 1 is a vertical sectional view through the improved jack showing the operating handle in folded inoperative position;

Figure 2 is a detail sectional view through the lifting head of the jack showing the valve mechanism actuated to release the pressure from the lower portion of the jack;

Figure 3 is a similar view showing the valve mechanism in normal position;

Figure 4 is a horizontal sectional view on the line 4—4 of Figure 2 showing the communicating duct between the intake tube and the annular groove in the tapered plug mounted in the lifting head;

Figure 5 is a detail view showing the tapered plug removed from the head;

Figure 6 is a detail sectional view on the line 6—6 of Figure 8 showing a modified construction with the valve mechanism in normal position.

Figure 7 is a similar view showing the valve mechanism in open position to release

the fluid from the lower portion of the jack; and

Figure 8 is a horizontal sectional view on the line 8—8 of Figure 7.

The body portion and the operating handle of the novel jack featured in the invention are similar in construction and operation to the form of jack shown in the above mentioned pending application and it will therefore be unnecessary to describe same in detail.

As shown in Figure 1, the jack comprises a cylinder 10 mounted in a suitable base 11 and having a hollow ram or plunger 12 reciprocally mounted therein. A packing nut 13, having a suitable packing 14 therein, is mounted upon the upper end of the cylinder 10 to provide a leak-proof joint between the plunger and cylinder. An annular ring 15 is seated against the upper end of the cylinder 10 to provide a seat for the packing 14. This ring also functions to limit the upward movement of the plunger 12 within the cylinder as a result of the plunger being reduced in diameter to provide an annular shoulder 16 adapted to engage the ring 15 when raised to the limit of its upward movement.

A shouldered disc 17 is mounted upon the lower end of the plunger 12 to provide a closure therefor, and this disc is securely clamped thereto by means of the intake and discharge tubes 18 and 19 having their upper ends seated in threaded sockets provided in the lifting head 21 as shown. A suitable packing 22 is seated against the disc 17 and is secured thereto by means of a plate 23 and the nuts 24 and 25 mounted in threaded engagement with the intake and discharge tubes 18 and 19. The nut 24 is open as shown to provide a communicating passage between the lower portion and cylinder 10 and the discharge tube 19, while the nut 25 provides a closure for the lower end of the intake tube 18 to prevent the passage of fluid therethrough.

An important feature of this invention resides in the novel construction of the valve mechanism mounted in the lifting head 21 of the jack. This valve mechanism consists primarily of two ball check valves which function to control the flow of liquid between the interior of the plunger 12 and the lower portion of the cylinder 10. As shown in Figures 1, 2, and 3, a horizontal passage 26 is provided in the lifting head 21 and has one end communicating with a tapered bore

27 in which a tapered plug 28 is rotatively mounted. This plug is preferably retained in the bore 27 by means of a compression spring 29 having one end bearing against a washer 31 seated against the hub 32 of the head 21, and having its opposite end seated against the inner face of a cap 33 which is retained upon the reduced end-portion 34 of the plug by means of a pin 35. An annular groove 38 is provided in the plug 28 in alignment with the horizontal passage 26. A port 37 connects the groove 36 with the duct 38 axially provided in the plug having one end communicating with the intermediate handle section 39 mounted in a hub 41 provided in one end of the plug as shown in Figures 4 and 5. A valve chamber 42, having a ball check valve 43 mounted therein, is arranged in the head 21 above the discharge tube 19 and communicates therewith through an upright passage 44 as shown. A compression spring 40 is mounted in the chamber 42 to retain the valve 43 in closed position. Thus it will be seen that when the valve 43 is open, communication will be established between the lower portion of the cylinder 10 and the intermediate handle section 39.

A similar check valve 45 is mounted in a valve chamber 46 directly above the intake tube 18 and similarly communicates therewith through an upright passage 47 as shown in dotted lines in Figures 1, 2, and 3. This valve is normally held against its seat by means of a compression spring 48 in a manner similar to that shown and described with reference to the valve 43. Referring to Figure 4, it will be noted that the intake tube 18, and therefore the upright passage 47, are offset from a line drawn through upright passage 44 of the tube 19 and the annular grooves 36 of the plug 28. The tube 18 is preferably offset as described above in order to simplify the construction of the valve chamber 48 and also to eliminate interference between the valve ports and passages provided in the head 21. The horizontal passage 26 leading from the discharge tube 19 communicates with the valve chamber 46 through a duct 49 as shown in Figures 1, 2, and 3, so that when the pump is actuated the fluid may be drawn from the interior of the plunger 12 into the passage 26, and thence into the annular groove 36 communicating with the intermediate handle section 39.

The means provided for pumping the fluid from the interior of the plunger 12 and forcing it beneath the packing or piston 22 to raise the jack, preferably consists of a pump mounted in a section of the operating handle. The form of operating handle shown in connection with this jack consists of the intermediate section 39 and a pump section 51 having a pivotal connection with the section 39 through a tapered joint 52 as shown in

Figure 1. A pump rod 53 is reciprocally mounted within the pump section 51 and is operable by means of hand grip 54 provided thereon as shown. Suitable means such as the stuffing box 55 are provided upon the pump section of the handle to prevent oil leakage therefrom when the jack is in operation and when it is stored away in a tool box or similar place.

When the pump rod 53 is outwardly drawn from the pump section 51 of the jack handle, oil will be drawn from the interior of the plunger 12 into the intake tube 18 through a duct 56, thence through the upright passage 47 and into the valve chamber 46, the flow of oil unseating the valve 45 and the oil flowing through the duct 49 into the horizontal passage 26, thence into the groove 36, port 37, duct 38, intermediate handle section 39, and into the pump section 51. Upon the return or inward stroke of the pump rod 53, the oil or fluid drawn into the pump section of the handle, will be forced therefrom back into the horizontal passage 26 and against the ball check valve 43, thereby causing it to open and permit the oil to flow into the discharge tube 19 and thence into the lower portion of the cylinder 10 with the resultant raising of the plunger 12 within the cylinder. Such flow of oil through the lifting head 21 will cause the check valve 45 to be seated so that all of the liquid drawn into the pump will be forced into the lower portion of the cylinder beneath the piston. Thus, it will be noted that continued reciprocal movement of the pump rod 53 will cause the liquid contained within the hollow plunger 12 to be forced into the lower portion of the cylinder beneath the piston, thereby causing the plunger to rise until the movement of the pump rod 53 is interrupted, or, until the annular shoulder 16 of the plunger engages the stop rod 14 adjacent the upper end of the cylinder.

The means provided for releasing the fluid under pressure from the lower portion of the cylinder and permitting it to flow back into the interior of the plunger, as when lowering the jack, preferably consists of a thrust member 57 mounted within the horizontal passage 26 and having one end adapted to engage the valve 43 as particularly shown in Figure 2. The opposite end of this thrust member is adapted to be engaged by a cam 58 secured to the tapered plug 28 in alignment with the thrust member. This cam, therefore, is preferably seated in the bottom of the annular groove 36 as shown in Figures 1, 2, and 3, and is relatively narrower than the groove 36 so as to permit the oil to flow thereby when the valve 43 is open. In Figures 1 and 3 the thrust member 47 is shown out of engagement with the cam 58 and the check valve 43 is therefore seated by the action of the spring 40. Figure 1

illustrates the position of the handle when folded against the body of the jack as when placed in a tool box or other storage place; while Figure 3 illustrates the approximate angle of the handle with relation to jack body when the pump is being operated to raise the plunger. Figure 2 illustrates the position of the intermediate handle section 39 when it is desired to open the check valve 43 to permit the fluid to flow from the lower portion of the cylinder back into the interior of the plunger as when lowering the jack. A groove or recess 59 is provided in the periphery of the tapered plug 28 and leads from the annular groove 36 to a port 61 having its lower end communicating with the upright passage 47, as particularly shown in Figure 4. This groove 59, it is to be understood, communicates with the port 61 only when the cam 58 engages the thrust member 57 to open the check valve 43. Thus it will be noted by reference to Figures 2 and 4, that when the check valve 43 is in open position as shown in Figure 2, the groove 59 will be in registration with the port 61, thereby establishing communication between the discharge tube 19 and the intake tube 18 with the result that the liquid under pressure in the lower portion of the jack will flow therefrom through the discharge tube 19, head 21, through the intake tube 18 and back into the interior of the plunger 12. By this simple valve mechanism, therefore, it will readily be seen that the lowering of the jack may be simply and conveniently affected by simply oscillating the intermediate handle section 39 until the groove 59 is brought into registration with the inclined port 61 as shown in Figures 2 and 4. The downward movement of the plunger may thus be controlled or interrupted at will by simply oscillating the intermediate handle section 39 as above described.

In devices of this type it is usually necessary that means be provided for admitting air into the hollow plunger 12 during the lifting operation of the jack and also that air thus drawn into the plunger may be permitted to escape therefrom when the jack is being lowered to its normal position. A vent hole 62 is therefore provided in the upper portion of the hollow plunger 12 at a point slightly below the lower face of the lifting head 21, shown in Figures 1, 2, and 3. This vent hole is so located that when the plunger 12 is in its normal retracted position, as shown in Figure 1, it will be moved downwardly into the packing nut 13 of the cylinder, thereby closing the vent and thus preventing the liquid within the plunger from leaking out of the jack. In the operation of the jack, as soon as the plunger rod is actuated and the plunger begins to rise within the cylinder, the vent 62 will move out of the packing nut 13 so that air may be drawn into the plunger

as indicated by the arrow in Figure 3. Such suction of air into the plunger will continue during the raising of the plunger and when the plunger is lowered the air thus drawn into the plunger will escape through the vent 62 as the liquid is being returned to the interior of the plunger as herein described.

From the foregoing, therefore, it will be noted that by the employment of this novel valve mechanism in connection with a jack of the type herein shown, the operation of such a jack will be positive and fool-proof. Its construction is also very simple and inexpensive and all parts are so arranged and assembled that they may readily be removed for repairs or replacement when necessary, thereby providing a mechanism which may be manufactured at a minimum cost.

Figures 6, 7, and 8 illustrate a modified construction wherein a check valve 43^a is mounted to be engaged directly by the cam 58 when it is desired to release the liquid, under pressure, from the lower portion of the cylinder and permit it to return to the interior of the plunger 12. In the construction here shown, a supporting member 63 is interposed between the spring 40^a and the plug 64 to provide a seat or support for the spring. This supporting member and also the spring 40^a and valve 43^a are mounted in a passage 65 which communicates with the discharge tube 19 through the upright passage 44 as shown. A valve cage 66, having a check valve 67 mounted therein and held against its seat by a spring 68, is mounted in a passage 69 substantially below the check valve 43, as shown in Figures 6 and 7. The valve chamber in the cage 66 communicates with the annular groove 36 of the plug 28 by means of a duct 69. A port 71 is provided in the opposite end of the cage 66 which communicates with the upright passage 47, leading from the intake tube 18, and also with an inclined port 72 having its upper end communicating with the tapered bore in which the plug 28 is mounted, in such a manner as to register with the groove 59 when the cam 58 is in valve-opening position as shown in Figure 7.

In the construction here shown, the oil is drawn from the intake tube 18 into the valve cage 66 and thence into the annular groove 36, it being understood that when the pump is being actuated the intermediate handle section 39 of the pump handle will be positioned as shown in Figure 6, or in such a manner that the cam 58 will be out of engagement with the ball check valve 43^a. During the suction stroke of the pump, the check valve 67 will open to permit the flow of oil, and during the pressure stroke of the pump, the valve 67 will be seated and the check valve 43^a will be opened to permit the liquid to flow from the pump through the passage 65 and into the discharge tube 19 to

the lower portion of the cylinder beneath the piston. When it is desired to lower the jack, the intermediate handle section 39 will be moved to the position shown in Figure 7, thereby causing the cam 58 to engage the ball valve 43^a with the result that it will be opened to permit the liquid under pressure in the lower portion of the cylinder to flow through the open valve and into the annular groove 36, from whence it will flow through the groove 59 and inclined duct 72 into the upper end of the intake tube 18 and back to the interior of the plunger.

I claim as my invention:

1. A lifting jack comprising in combination, a cylinder adapted to contain an inelastic fluid, a hollow plunger movable in said cylinder, a lifting head on said plunger having fluid passages connecting it with said cylinder and with the interior of said plunger, valves in said passages for controlling fluid flow therethrough when the plunger is raised, a pump having a pivot in said head, a by-pass in said pivot and said head for permitting the return of the fluid from the cylinder to the interior of said plunger, and means operable by rotation of said pivot to open one of said valves to allow the fluid in the cylinder to flow through said by-pass and return to said plunger to lower the jack.

2. A lifting jack comprising in combination, a cylinder adapted to contain an inelastic fluid, a hollow plunger movable therein, a lifting head on said plunger having fluid passages connecting it with said cylinder and with the interior of said plunger, a check valve in each passage adapted to control fluid flow therethrough when the plunger is raised, a plug valve pivotally mounted in said head and communicating with said passages, a pump operatively connected with said plug valve, a by-pass for permitting the return of the fluid from said cylinder to said plunger, a member in one of said passages adapted to engage the check valve mounted therein, and means on said plug valve for actuating said member to open its complementary valve, upon rotation of said plug valve, whereby the fluid in said cylinder is permitted to flow through said by-pass and return to said plunger to lower the jack.

3. A lifting jack comprising in combination, a cylinder, a hollow plunger movable therein, an inelastic pressure fluid, a lifting head on the plunger, check valves mounted in said head, means for connecting each valve with one side of the plunger, a tapered plug pivotally mounted in the head and having a pump operatively connected therewith, an annular groove in said plug communicating with said valves, a by-pass in said plug and said head functioning to provide a passage for returning the fluid from the cylinder to

the plunger, and a cam secured to said plug and rotatable therewith to open one of said valves to permit the fluid in the cylinder to return through said by-pass to the plunger, when the lifting head is being lowered.

4. A lifting jack comprising in combination, a cylinder, a hollow plunger movable therein, an inelastic pressure fluid, a lifting head on the plunger, check valves in said head, means for connecting each valve with one side of the plunger, a tapered plug rotatably mounted in said head and having a pump operatively connected therewith, an annular groove in said plug, a communicating passage between said groove and one of said valves, a by-pass in said plug and said head functioning to provide a passage for returning the fluid from the cylinder to the plunger, means in said communicating passage adapted to be engaged by means on said plug valve, when the latter is rotated a predetermined distance, to cause the valve in said passage to be opened to permit the passage of fluid from the cylinder through said by-pass and into the interior of the plunger to lower the jack.

5. A lifting jack comprising in combination, a cylinder, a plunger operable therein, an inelastic pressure fluid, a lifting head on the plunger, a plug valve rotatably mounted in the head and having fluid ducts connecting it with each side of the plunger, a check valve in each duct, a pump operatively connected with said plug valve, an annular groove in the periphery of said plug, a normally closed by-pass connecting said annular groove with the interior of said plunger, a thrust member movably mounted in one of said ducts and normally projecting into said groove, and a cam secured to said plug and adapted to actuate said thrust member, when the plug is rotated, to cause the check valve adjacent to said member to open and permit the fluid in the cylinder to return from the cylinder to the interior of said plunger, through said by-pass.

6. A lifting head comprising in combination, a cylinder having a plunger operable therein, a reservoir, a lifting head on the plunger, a plug valve in said head, a pump connected with said plug valve and adapted to rotate the latter, passages in said head connecting said plug valve with the cylinder and the reservoir, a check valve in each of said passages, a cam on the plug valve, means in one of said passages actuatable by said cam to open the check valve in said passage, and a by-pass through the plug valve and said head connecting the closing sides of said check valves.

In witness whereof, I have hereunto set my hand this 26th day of September, 1925.

TIMOTHY C. POMEROY.
